FIG. 1.

FIG. 12.

FIG. 2.

The drawing shows a cross-section of a device. At the top, the text 'FIG. 3.' is written above a horizontal line. Below this line is a rectangular frame. The left side of the frame has a vertical column with numerical markings: '23' at the top, '18' in the middle, and '22' at the bottom. The right side of the frame has a vertical column with markings: '18' at the top, '21' in the middle, and '21' at the bottom. Inside the frame, there is a central rectangular area with diagonal hatching. To the left of this area is a vertical column with diagonal hatching, labeled '22' at its base. To the right is another vertical column with diagonal hatching, labeled '21' at its base. The bottom of the frame contains several numerical labels: '65' in the center, '66' on the right, '29' on the left, and '24' at the bottom center. There are also small numbers '13' and '15' located on the far right and bottom right respectively. The entire drawing is enclosed in a rectangular border.

NOZZLE FOR STRIPING MACHINE

Samuel B. Beugler, Los Angeles, Calif.

Application February 1, 1949, Serial No. 73,981

2 Claims. (Cl. 91—30)

1

This invention relates to a striping machine for applying striping fluid to horizontal flat surfaces such as floors, pavements and the like.

The primary object of the invention is to provide a machine of the above character adapted to be advanced on the surface to be striped and operated to feed striping fluid to the surface in such fashion as to define a line while the machine is advancing and in which means are provided to prevent discharge of the striping fluid when the machine is at rest.

Another object is to provide a striping machine which may be readily moved over a surface on which it is supported and be manipulated by a person while walking or standing and to which end embodies a carriage fitted with a running gear, a handle for directing movement thereof, a mounting for a container of striping fluid, and nozzle and applicator for feeding the striping fluid from the container and applying it to a surface to form a stripe, and a leading runner for enabling directing the carriage along a line.

Another object is to provide a construction in the nozzle and applicator whereby the parts thereof may be readily disassembled and reassembled to facilitate cleansing thereof and also to provide a construction whereby the nozzle may be readily attached to the carriage and removed therefrom.

Another object is to provide a construction in the applicator whereby it will serve as a valve to close the nozzle and prevent the discharge of striping fluid therethrough when the applicator is elevated to a position out of contact with the surface traversed by the carriage, and which is operable to open the nozzle to the flow of striping fluid therethrough when the applicator is brought to bear under pressure of the surface to be striped.

Another object is to provide an effective means for raising and lowering the applicator relative to a surface on which the machine is supported.

With the foregoing objects in view together with such other objects and advantages as may subsequently appear, the invention resides in the parts and in the combination, construction and arrangement of parts hereinafter described and claimed, and illustrated by way of example in the accompanying drawings, in which:

Fig. 1 is a view of the striping machine as seen in side elevation with part of the handle portion thereof broken away and showing certain adjustable parts thereof in alternate position in full and dotted lines:

Fig. 2 is a view in plan and horizontal section taken on the line 2—2 of Fig. 1 with the nozzle and its associated applicator removed:

Fig. 3 is a detail in vertical section taken on the line 3—3 of Fig. 1:

Fig. 4 is a view in section and elevation taken on the line 4—4 of Fig. 1:

2

Fig. 5 is a plan view of the machine with portions broken away:

Fig. 6 is an enlarged vertical section of the nozzle and applicator as detached and as seen on the line 6—6 of Fig. 5: showing the applicator in the nozzle closing position:

Fig. 7 is a section of a fragmentary portion of the nozzle and applicator shown in Fig. 6 depicting the applicator in the nozzle opening position:

Fig. 8 is a plan view of the nozzle and applicator with portions broken away:

Fig. 9 is a fragmentary inverted plan view of the nozzle and applicator:

Fig. 10 is a detail in section and elevation taken on the line 10—10 of Fig. 8:

Fig. 11, Sheet 1, is a detail in section and elevation as seen on the line 11—11 of Fig. 1:

Fig. 12, Sheet 1, is a sectional view of the handle taken on the line 12—12 of Fig. 1.

Referring to the drawings more specifically A indicates generally a carriage which embodies a bed plate 15 fitted at its forward end with an axle 16 on which is revolubly mounted a pair of wheels 17—17. A pair of parallel rocker arms 18—18 pivotally supported on pivot pins 19—19 carried on the rear side portions of the bed plate 15 extend longitudinally along each side of the bed plate and to the rear thereof and have wheels 20—20 revolubly mounted on the rear ends thereof. The wheels 17—17 and 20—20 align with each other and constitute the running gear of the carriage A. Extending transversely beneath the bed plate 15 and carried thereby is a rock shaft 21 fitted at each side of the bed plate with finger cams 22—22 which engage the lower edges of the forward end portions of the rocker arms 18—18. The rock shaft 21 is fitted with an operating lever 23 which extends upwardly at one side of the bed plate 15 and whereby the rock shaft 21 may be turned to cause the finger cams 22—22 to move upwardly and effect elevation of the forward ends of the rocker arms 18—18 and thereby elevate the rear marginal portion of the bed plate 15 with the latter swinging on the front axle 16 as on a fulcrum, or to cause the finger cams to move downwardly to permit downward movement of the rocker arms 18—18 and the rear portion of the bed plate 15 under the weight of the latter and of the load imposed thereon.

Formed on the underside of the rear portion of the bed plate 15 is a tube 24 which extends along the longitudinal center of the bed frame and opens upwardly at its forward end through the latter as indicated at 25 in Fig. 2; the tube 24 terminating at its rear end contiguous the rear edge of the bed plate 15 as indicated at 26 in Fig. 2. The rear end of the tube 24 is designed to receive in telescopic engagement therewith the tubular end 27 of a nozzle B which end

is cylindrical and conformable to the inner periphery of the outer end 26 of the tube 24. A flange 28 is formed on the cylindrical end 27 of the nozzle and is adapted to abut the end 26 of the tube 24 against which the flange 28 is tightly but releasably held by a bale 29 pivoted at its ends 30—30 in sockets 31—31 on the body 32 of the nozzle B. The bale 29 is detachably engageable with the forward end of the tube 24 in clamping engagement therewith; the forward end of the tube 24 being rounded or inclined to effect wedge engagement with the bale 29.

The body 32 of the nozzle B is rectangular in plan and is formed with a chamber 34 opening through the cylindrical end of the nozzle and also opening through a slot 35 in the outer end of the nozzle which end is elongated transversely and embodies a bottom wall 36, a top wall 37 and end walls 38—38.

The nozzle top wall 37 extends in angular relation to the bottom wall 36 and has its outer edge 39 inwardly offset relative to the outer edge 40 of the bottom wall 36. Ledges 41—41 are formed on the inner faces of the end walls 38—38 extending in continuation of the upper face of the top wall 37, and seating on the ledges 41—41 and the upper face of the wall 37 is a removable flexible metallic plate 42 the forward edge 43 of which extends parallel with the forward edge 40 of the nozzle bottom wall 36 and is spaced inwardly therefrom forming a gap 44 between the edges 40 and 43 which gap constitutes the discharge outlet of the nozzle B. Seating on the plate 42 is an elastic sheet 45 formed of rubber or similar material which projects over the nozzle outlet 44 and has its forward marginal portion projecting beyond the nozzle edge 40 and is adapted to be seated on the latter to close the nozzle outlet 44 or to be spaced relative to the edge 40 to open said outlet. The outer edge 46 of the flexible sheet 45 extends parallel with the edge 40 which edges together with the edge 43 of the plate 42 are straight and coextensive throughout the width of the nozzle outlet 44. Seated on the upper face of the flexible sheet 45 is a thin flexible metallic plate 47 the forward edge 48 of which is spaced inwardly from the forward edge 46 of the flexible sheet 45. The assembly consisting of the plate 42, sheet 45 and plate 47 is engaged by a pair of studs 49—49 projecting upwardly from the nozzle top wall 37 and is held in place in clamped engagement with the nozzle by a clamping bar 50 which seats on the plate 47 and is engaged by the studs 49; the bar 50 being held in place by a bale 51 the ends 52—52 of which are pivoted in sockets in the outer faces of the nozzle end walls 38—38; the intermediate portion of the bale 51 having snap clamping engagement with a notch 53 formed on a contoured lug 54 formed on and projecting upwardly from the central portion of the clamping bar 50. Formed on the bar 50 and projecting forwardly of its forward edge and at each end thereof are extensions 55—55 arranged to bear upon the end margins of the elastic sheet 45 at the ends of the plate 47 which are inset to clear the extensions 55 as particularly shown in Fig. 8 so as to hold the ends of the plate 42 and the mid portion of the ends of sheet 45 against displacement of the ledges 41.

The outer edge of the flexible sheet 45 constitutes an applicator for applying and spreading striping fluid discharged from the nozzle and to form a stripe of such fluid while the nozzle is

being advanced as will hereinafter be more fully described; the under side of the outer marginal portion of the flexible sheet 45 being formed with a series of short grooves 56, particularly shown in Fig. 9, which grooves lead from the inner portion of that part of the sheet 45 protruding beyond the nozzle end edge 40 and opening to the outer end of the sheet. The grooves 56 serve to uniformly feed and distribute the striping fluid passing therebeneath with a brushing action.

Means are provided for automatically clamping the forward marginal portion of the sheet 45 against the edge 40 to close the outlet 44 which as here shown comprises a rocker bar 57 extending transversely of the under side of the nozzle body and pivotally connected at its end portion to the latter by pivot pins 58—58 and which rocker bar is formed at its ends with parallel shoes 59—59 extending alongside the end walls 38 of the nozzle and protruding rearwardly thereof; the shoes being formed with upstanding lugs 60—60 affording a support for the end portions of a removable rod 61 extending over and abutting the forward marginal portion of the plate 47. One end portion of the rod 61 is formed with an angular extension 62 overlying one of the shoes 59 and having spring engagement with a lug 63 on the latter whereby the rod 61 is releasably held in place. Springs 64—64 bear between the under side of the nozzle bottom wall 36 and a forward marginal portion of the bar 57 forwardly of the pivots 58—58 at each end portion of the bar 57, which springs normally press the shoes 59—59 downwardly to cause the bar 61 to bear on and bend the outer marginal portions of the plate 47 and sheet 45 downwardly to bring the under side of the sheet 45 tightly against the edge 40 as shown in Fig. 6, when the shoes are clear of the surface on which the machine is supported. The shoes 59 are adapted to be swung upwardly relative to the nozzle B on being brought into engagement with the surface on which the machine is supported so that the outer margin of the flexible sheet 45 will be bent upwardly as shown in Fig. 7 to clear the edge 40 when the outer margin of the sheet 45 is brought to bear under pressure on such surface.

The bed plate 15 is adapted to receive and afford a support for a container C of striping fluid, which container is here shown as comprising an ordinary paint bucket the bottom wall 65 of which is seated in a recess 66 on the bed plate 15 and is formed with an opening 67 arranged over the opening 25 of the tube 24 through which contents of the container C are delivered through the tube 24 to the nozzle B and its associated applicator. The container C is rigidly held in place on the bed plate 15 by clamp bars 68 having inturned flanges 69 on their upper ends positioned in engagement with the upper margin of the container and having out-turned flanges 70 on their lower ends secured by screws 71 to the bed plate 15. The container C is fitted with a removable cover 72 having an upstanding central post 73 formed with a notch 74 in its upper end to receive a bale 75 with which the container C is equipped and whereby the cover 72 is held in place.

The carriage A is equipped with a handle D by which it may be shoved to traverse a surface which handle embodies a yoke 76 the side members 77—77 of which are pivotally connected to the pivots 19—19 for vertical swinging movement of the yoke 76 to various upwardly extending

angular positions relative to the bed plate 15. Connected to the central portion of the yoke 76 is a tubular stem 78 leading upwardly to a suitable handle, not shown, in which stem is mounted a longitudinally moveable rod 79 the lower end of which projects through the yoke 76 into normal engagement with a notched segmental rack 80 carried by the bed plate; a spring 81 bearing between a collar 82 on the rod 79 and a collar 83 internally of the tubular shaft 78 urging the rod 79 to its rack engaging position. The upper end of the rod 79 is turned outwardly through a longitudinal slot 84 in the shaft 78 and is fitted with a knob 85 by which the rod may be manually shifted longitudinally to draw the lower end thereof out of engagement with the rack 80 to permit shifting of the yoke 76 into the desired angular position relative to bed plate 15.

As a means for cushioning relative movement of the rocker arms 18-18 and the bed plate 15 each of the rocker arms is equipped with a yoke 86 one leg of which is affixed to the rocker arm and the other of which carries a protruding downwardly extending coil spring 87 the lower end of which is disposed to abut the bed plate to cushion and limit downward movement of the forward end portions of the rocker arms relative to bed plate.

Mounted on the axle 16 for a vertical swinging movement is an arm E here shown as comprising spaced side members 88-88 between the outer ends of which is mounted a revoluble wheel 89. The arm E normally extends forwardly of the carriage A with the wheel 89 bearing on the surface supporting the carriage at a point in advance of the latter in line with its longitudinal center and that of the nozzle and applicator to serve as a guide to the operator in directing the carriage along a line. When not in use the arm E may be swung upwardly into the dotted line position shown in Fig. 1 where a transverse rod 90 extending between the inner portions of the side members 88-88 of the arm is sprung into engagement with a contoured lug 91 projecting from the forward end of the bed plate 15.

A coil spring 92 wound around the axle 16 has one end thereof engaged with the lug 91 and its other end engaging the lower edge of an extension 93 on one of the arm side members 88. The spring 92 is tensioned to yieldably hold the arm E in its forwardly extending position; the spring however being sufficiently weak that the engagement of the rod 90 with the lug 91 when the arm E is in its upright position will retain it in such position in opposition to the spring 92. When the arm E is forwardly extended the spring 92 will exert such down pressure on the arm E as to hold the wheel 89 against the supporting surface.

In the operation of the invention when it is desired to move the carriage over a surface without effecting a striping action the applicator strip 45 is disposed out of contact with the surface on which the carriage is supported which is effected by elevating the rear portion of the bed plate 15 relative to such surface by disposing the finger cam 22 on the rock shaft 21 so as to support the forward ends of the rocker arms 18-18 in their uppermost positions as shown in Fig. 1. When it is desired to effect a striping action the rock shaft 21 is turned through the medium of the lever 23 to swing the finger cams 22-22 rearwardly and downwardly thereby permitting the forward portions of the rocker arms 18-18 and the rear portions of the bed plate 15 to swing

downwardly to bring the outer margin of the applicator sheet 45 and the shoes 59-59 into contact with the surface to be striped and causing the outer edge 46 of the sheet 45 and the shoes 59-59 to swing upwardly relative to the nozzle under the urge of the load imposed through the latter from the bed plate 15. The nozzle outlet 44 will then be open as shown in Fig. 7 so that the striping fluid may flow to discharge through the nozzle and on advance of the carriage A be distributed by the applicator to form a stripe.

In order to facilitate advancing the carriage along a line the arm E is swung to its lowered forwardly extending position so that the wheel 89 on the outer end thereof will seat on the surface being striped in advance of the carriage and then serve as a guide to the operator who directs movement of the carriage through the medium of the handle D then disposed in its desired angular relation to the bed plate to facilitate shoving of the carriage. When the stripe is formed of desired length the flow of striping fluid may be stopped either by lifting the rear portion of the carriage through the medium of the handle D so as to elevate the shoes 59-59 clear of the striped surface or by manipulating the lever 23 to swing the forward ends of the arms 18 upwardly. By lifting the rear portion of the carriage by means of the handle D it may be advanced on its forward wheels 17-17 while so elevated to a desired position and again lowered to its stripe forming position, thus obviating the operation of the lever 23 to cut off the flow of the striping fluid as when momentarily breaking a stripe or in turning the carriage around.

A feature of the invention resides in the construction of the nozzle and applicator whereby the applicator may be readily removed and the parts separated for cleansing purposes, which is accomplished by freeing the clamping bar 50 by moving the bale 51 out of engagement with the lug 54 then lifting the bar and the applicator assembly free of the studs 49. The nozzle B may be detached from the carriage when so desired by disengaging the bale 29 from the forward end of the tube 24 and withdrawing the cylindrical end 27 of the nozzle out of engagement with the outer end of the tube 24.

When the striping fluid content of the container C has been drained therefrom the container may be refilled on removing the cover 72 which is quickly effected by disengaging the bail 75 from the post 73 and lifting the cover free of the container.

I claim:

1. In a striping machine, a nozzle having an elongated discharge outlet, a wall forming the margin of the under side of said outlet having a straight forward edge, a wall spaced from said first named wall having a forward margin off-set rearwardly from the margin of the first named wall, a flexible metallic plate seated on said last named wall projecting beyond the forward margin of the latter and having an edge spaced inwardly from the margin of the first named wall and defining with said margin the nozzle discharge outlet, a flexible applicator sheet overlying said plate having a marginal portion protruding beyond the margin of said first named wall, a flexible metallic plate overlying said sheet and means for detachably clamping the assembly of the metallic plate and the flexible sheet on said nozzle.

2. The structure called for in claim 1 together

with spring pressed means bearing on the plate imposed on the flexible sheet normally holding the latter against the margin of the nozzle discharge outlet to normally close the latter; the outer margin of said flexible sheet and plate being moveable upwardly under pressure applied to the underside of the outer marginal portion of said flexible sheet to move the latter in opposition to said spring pressed means to open said nozzle discharge outlet.

SAMUEL B. BEUGLER.
